Specification for Design.

Patented Jan. 7, 1913.

Application filed November 6, 1912. Serial No. 729,907. Term of patent 8½ years.

To all whom it may concern:

Be it known that I, ADOLPH PETZOLD, a citizen of the United States, residing in the city of Philadelphia, State of Pennsylvania, have invented a certain new, original, and ornamental Design for Rugs, of which the following is a specification, reference being had to the accompanying drawing, forming part thereof.

The figure is a plan view of a quarter section of an Axminster rug, the other three quarter-sections being identical therewith, showing my new design.

I claim:—

The ornamental design for a rug, as shown.

ADOLPH PETZOLD.
